UNITED STATES PATENT OFFICE.

JOSEPH L. STEVENS, OF STOCKTON, KANSAS.

SEAT-COVER.

1,264,573.

Specification of Letters Patent. Patented Apr. 30, 1918.

Application filed December 22, 1916. Serial No. 138,402.

To all whom it may concern:

Be it known that I, JOSEPH L. STEVENS, a citizen of the United States, residing at Stockton, in the county of Rooks and State 5 of Kansas, have invented certain new and useful improvements in Seat-Covers, of which the following is a specification.

This invention has relation to water closet seats, and has for an object to provide a 10 sanitary protective device in the form of a water closet mat, which is covered with a temporary cover of paper or the like having an aperture therein, said cover being subsequently removed from the device after use 15 and another substituted.

Another object of the invention is to provide a mat of the character set forth which may be folded up and carried about the person and available for immediate use.

20 In addition to the foregoing, my invention comprehends improvements in the details of construction and arrangement of parts to be hereinafter more fully described and particularly set forth in the appended 25 claims.

In the accompanying drawings in which similar and corresponding parts are designated by the same characters of reference throughout the several views in which they 30 appear—

Figure 1, is a view in top plan of a removable water closet seat constructed after the manner of my invention.

Fig. 2, is a transverse section taken on 35 the line 2—2 of Fig. 1, and

Fig. 3, is a detail enlarged sectional view taken on the line 3—3 of Fig. 1.

With reference to the drawings the device comprises a mat designated 1 of rubber 40 or other pliable yielding material, circular in configuration, and severed at one portion of its circumference as indicated at 2. The upper portion of the mat is provided with a plurality of upstanding vertical studs 3.

45 To use the device a temporary covering of paper or other material is provided, and comprises a circular upper portion 4 which covers the upper surface of the mat from the outer edge thereof to a distance adjacent 50 the inner edge, said cover being formed with a lower portion 5, which extends beneath the mat, and is provided with a more or less elliptical aperture 6 which is intersected at one end by an opening 7, coinciding with the opening 2 of the mat. 55 This covering may be formed in one piece,

or may be formed of an upper and a lower portion connected at their circumferential edges. Openings 8 are provided in the upper member 4 of the covering through 60 which studs 3 pass and whereby said cover is retained in proper relation to the mat. The studs adjacent the severed portion 2 of the mat may be connected by means of a resilient band or the like 9 whereby the mat 65 is retained in proper place. The mat may also be given a tendency to spread outward so as to place the covering under strain, and to provide thereby a flat surface. The mat having thus been covered the device is 70 laid upon the water closet thereby forming a sanitary cover for the same and preventing bodily contact with the water closet seat, and the consequent transmission of disease. The outer covering may be subsequently removed and another substituted. 75

Thus it will be seen that I have provided a novel device which owing to its composition is yielding and adapted to conform to the curvature of a water closet seat, and 80 which is furthermore adapted to be folded and carried about in a hand bag or the like.

Having thus described my invention what I claim as new and desire to secure by Letters Patent is:—

1. A water closet seat cover, including an annular mat of yielding material severed at one point, a temporary removable cover therefor disposed at the lower and upper portions of said mat, means for securing 90 said cover to the mat and means for connecting the ends of said mat.

2. A water closet seat cover, including an annular mat of rubber severed at one point transversely, a temporary removable cover 95 therefor extending partially over the upper surface of the mat, and entirely there beneath, said cover at its lower portion having an elliptical opening and a radial opening intersecting said elliptical opening, and coinciding with the severed portion of the mat, means on the mat for securing the cover thereto, and resilient means for connecting the ends of the mat.

3. A water closet seat cover, including an 105 annular mat of rubber or the like, having one portion thereof severed transversely, a temporary removable cover for the mat, having one portion thereof severed transversely, said cover at its lower portion having 110 an elliptical opening and a radial opening intersecting said elliptical opening and

coinciding with the severed portion of the mat, means on the mat for securing the cover thereto, and resilient means for connecting the ends of the mat.

- 5 4. A water closet seat cover, including an annular mat of rubber or the like, having one portion thereof severed transversely, a temporary removable cover for the mat including an upper portion partially covering the top of the mat, and having a plurality of openings, a corresponding number of studs formed integrally with the mat and extending through said openings to retain

the cover thereon, said cover having a lower cover extending entirely beneath the mat, and provided with a substantially elliptical opening intersected by a radial opening, said opening coinciding with the severed portion of the mat, and a resilient elastic band connecting the ends of the mat.

In testimony whereof I affix my signature in presence of two witnesses.

JOSEPH L. STEVENS.
